UNITED STATES PATENT OFFICE.

ERNEST JOSEPH MARTIN, OF NEW ROCHELLE, NEW YORK.

ARTIST'S FRAME.

Application filed January 26, 1922. Serial No. 532,055.

To all whom it may concern:

Be it known that I, ERNEST J. MARTIN, a citizen of the United States, and a resident of New Rochelle, in the county of Westchester and State of New York, have invented new and useful Improvements in Artists' Frames, of which the following is a full, clear, and exact description.

This invention relates to artists' frames and was primarily designed for use by scenic artists.

One of the difficulties that often confront scenic artists is how to support a flexible paint receiving foundation of large dimensions in a room of comparatively small dimensions, thus eliminating the necessity of providing a building of sufficient size to house the paint receiving foundations of the greatest size that they may be required to operate upon in the carrying on of their work. Once such a problem has been solved it is possible for the scenic artists to carry on work on all sizes of paint receiving foundations without making a large outlay to provide a building of sufficient size to accommodate all sizes of foundations that he may find it necessary to work upon.

The general object of this invention is the provision of an artist's frame for supporting flexible paint receiving foundations of dimensions several times that of the cross-section of the building or room in which it is desired to work.

A further object is the provision of an artist's frame capable of adjustment to accommodate various sizes of paint receiving foundations.

Another object is the provision of an artist's frame which supports the painting face in such a position that it slopes away from the vertical towards the bottom.

This object is accomplished by providing roller supporting means spaced in triangular relation for supporting the paint receiving foundation and providing means in conjunction with the roller supporting means for varying the distance between any two of the rollers so as to accommodate paint receiving foundations of different sizes and so locating two of the rollers that a portion of the paint receiving foundation is retained in a position sloping away from the vertical towards the bottom.

These and other objects of the invention will be more clearly understood from the

following detailed description and accompanying drawings, of which—

Figure 1 is a side elevation of the artist's frame with a paint receiving foundation mounted thereon;

Figure 2 is an end elevation of the artist's frame;

Figure 3 is a section along the line 3—3, Figure 4; and

Figure 4 is a section along the line 4—4, Figure 2.

Referring to the above-mentioned drawings, two end supporting posts 10 and 11 are shown attached to the ceiling 12 and floor 13 of any room or building in which the frame may be located, and a center supporting post 14 carried by means of braces 15, 16, 17 and 18 is attached to the end supporting posts 10 and 11. Each of the posts 10, 11 and 14, have two brackets 19 and 20 attached thereto which are provided with bearings in which the shafts 21 and 22 are mounted respectively. A curved arm 23 provided with a trunnion 24 is provided in conjunction with each post and supported on each post by means of a bracket 25 which has a slot 26 cut therein in which the trunnion 24 moves. A shaft 27 is journaled in these arms. A rod 28 is slidably mounted in guides 29 and 30 mounted on each post, and the upper end of each rod 28 is connected to the curved arm 23 mounted on the corresponding post. Each rod 28 is operated by means of a connecting rod 31 and a bell crank 32 which is fixed to a shaft 33 journaled in brackets 34 carried by the posts. A gear 35 is mounted on the shaft 33 and is operated by means of a worm gear 36 mounted on the post 10. This worm gear is operated by means of a crank 37.

In this particular construction, as shown in Figure 4, two rollers 38 are loosely mounted on each shaft. These rollers are provided with grooves 39 in which belts 40 are located. These belts 40 are provided with projection 41 which engage the paint receiving foundation 42 mounted upon the rollers so as to prevent the said paint receiving foundation from slipping thereon. Provided in the rollers 38 mounted on the shaft 21 are chambers 43 and 44. Located in each chamber and fixed to the shaft are collars 45 and 46 provided with pins 47 and 48, respectively. These pins 47 and 48 engage in openings provided in the disks 51

and 52 which are integral with the sleeves 49 and 50 forming a part of the rollers 38. Thus the rollers may be connected directly to the shaft 21. A lever 53 is pivotally supported on the post 10 by means of a bracket 54 and pin 55. A U-shaped portion 56 of the lever 53 engages a spool-shaped collar 57 fixed to the shaft 21, serving as a means for moving the shaft 21 endwise. The pins 47 as shown are of greater length than the pins 48 and so by the movement of the shaft either one or two rollers may be connected to the shaft so as to drive them upon the operation of the shaft. A grooved wheel 58 is fixed to each end of each shaft 21, 22 and 27, and a belt 59 extends around the wheels 58 located at each end of the frame. These wheels 58 and the belts 59 serve as a means for operating the shaft and, through the shafts and connecting devices mounted on the shaft 21, the rollers 38.

Four plates 60 are provided with a plurality of hooks 62 and eye members 63. These plates serve to engage the opposite ends of the paint receiving foundation 42, or a lacing 61 is supplied for attaching the eye members of the different plates 60 so as to connect the opposite ends of the paint receiving foundation 42 in order to hold the latter in position upon the rollers 38.

In order to give considerable rigidity to the center post 14, the braces 15 and 18 support the post through a cross arm 64 which is fixed to the post. Turnbuckles 65 are connected into the braces 15 to 18, inclusive, so that they may be adjusted to bring the center bearings supported by the center post 14 into alignment with the other bearings.

In using this frame the rollers 38 carried by the shaft 27 are moved to what is decided to be the proper distance from the rollers 38 carried by the shaft 21 so that the perimeter about all the rollers will be slightly greater than the length of the paint receiving foundation. The lever 53 is then operated connecting the rollers 38 on the shaft 21 to the shaft. The paint receiving foundation is then engaged with the projections 41 on the belts 40 and wound about the rollers. The hooks of the plates 60 are engaged in the opposite ends of the paint receiving foundation, and the eye members are connected together by means of the lacing 61. This holds the paint receiving foundation in position on the rollers. The lever 53 is then operated, moving the shaft 21, as seen in Figure 4, to the left, engaging the pins 47 and 48 in the disks 51 and 52, thus connecting the rollers to the shaft.

After this connecting operation has been completed the rollers may be operated by operating the belt 59 to move the paint receiving foundation to any desired position.

After the paint receiving foundation has been stretched upon the rollers the crank 37 might be operated to move the shaft 27 outwards so as to tension the paint receiving foundation 42. The operation of the mechanism for controlling the position of the shaft 27 is as follows: The worm gear 36 is operated by means of the crank 37, rotating the gear 35 and through it the shaft 33. This rotates the arms 32 towards a vertical position, forcing the rods 28 upward, moving the arms 23 outward thus moving the shaft 27 from the shaft 21.

The shafts 21 and 22 are so positioned with regard to the frame that the portion of the paint receiving foundation extending between them falls away from the vertical towards the bottom. The advantage of such a construction is that when drops of paint fall from the brush while the painting operation is carried on there is no danger of it coming in contact with the paint receiving foundation to streak the same.

It will be seen from the foregoing description that the shaft 21 may be connected to one or more of the rollers mounted thereon. This allows the frame to be used for paint receiving foundations which are small. A smaller paint receiving foundation extends over the rollers placed in triangular relation to one another, and by connecting one roller to the shaft 21 all the rollers are driven through the belt means 59. The belts which are located on the rollers 38 are adjustable so as to allow the shafts 27 and 21 to be set with different distances between them.

I would state in conclusion that while the illustrated example constitutes a practical embodiment of my invention I do not limit myself strictly to the exact details herein illustrated since manifestly the same can be considerably varied without departing from the spirit of the invention as defined in the appended claims.

Claims:

1. As a new article of manufacture, an artist's frame of the class described, for holding flexible paint receiving mediums comprising supporting members, three lines of rollers spaced in triangular relation to one another carried by the supporting members, one line of said rollers being mounted on arc-shaped plates carried by the supporting members, and means for adjusting said arc-shaped plates to increase the distance between two of the lines of rollers to accommodate different sized paint receiving mediums.

2. An artist's frame of the class described for holding a flexible paint receiving medium comprising supporting members, three lines of rollers spaced in triangular relation to one another carried by the supporting members, and means for adjusting one line of rollers to accommodate different sized

- paint receiving mediums, the other lines of rollers which are fixed being so positioned that the working face of the paint receiving medium is supported so that it recedes toward the bottom from a vertical line dropped from the upper roller. 5 so that the base of the triangle is at the top, 45 and means for varying the distance between the lines of rollers located at the top to accommodate different sizes of paint receiving mediums.
3. An artist's frame of the character described, comprising supporting members, a plurality of shafts mounted on said supporting members and spaced in triangular relation to one another, a plurality of rollers loosely mounted on each shaft, and means carried by one shaft for successively engaging and releasing rollers mounted on said 10 shaft. 7. As a new article of manufacture, an artist's frame of the class described for holding a flexible paint receiving medium comprising supporting members, a plurality of shafts spaced in triangular relation to one another carried by the supporting members, 55 rollers loosely mounted on each shaft, means for connecting the rollers mounted on one shaft to that shaft, means for driving the shafts, and means mounted on the rollers for carrying the paint receiving foundation 60 and for driving one line of rollers from another line of rollers.
- 15 4. An artist's frame of the class described for holding flexible paint receiving mediums comprising supporting members, three lines of shafts spaced in triangular relation 20 to one another carried by the supporting members, the base of said triangles being at the top of the frame, rollers loosely mounted on the shafts, means for varying the distances between the lines of shafts at the top 25 of the frame for accommodating paint receiving mediums of different sizes, means for connecting one or more of the rollers to a shaft, and means for operating the shaft and rollers to move the paint receiving medium. 5. An artist's frame of the character described, comprising supporting members, a plurality of shafts mounted in spaced relation on the supporting members, a plurality of rollers loosely mounted on each shaft, 30 means carried by one shaft for successively engaging and releasing the rollers mounted on said shaft, and means for operating said engaging and releasing means. 6. As a new article of manufacture, an artist's frame of the class described for carrying a paint receiving medium, comprising supporting members, three lines of rollers spaced in triangular relation to one another 35 so that the base of the triangle is at the top, 45 and means for varying the distance between the lines of rollers located at the top to accommodate different sizes of paint receiving mediums.
- 40 7. As a new article of manufacture, an artist's frame of the class described including a plurality of shafts and a plurality of rollers loosely mounted on each shaft, a device for attaching the rollers mounted on one shaft to that shaft comprising a plurality of collars attached to the shaft, means for moving the shaft endwise, and means carried by the collars for successively engaging the rollers as the shaft is moved endwise. 8. In an artist's frame of the class described including a plurality of shafts and a plurality of rollers loosely mounted on each shaft, a device for attaching the rollers mounted on one shaft to that shaft comprising a plurality of collars attached to the shaft, means for moving the shaft endwise, and means carried by the collars for successively engaging the rollers as the shaft is moved endwise. 9. An artist's frame of the class described for carrying a paint receiving foundation, comprising supporting members, three shafts 75 spaced in triangular relation to one another carried by the supporting members, a plurality of rollers loosely mounted on each shaft, means for driving the shafts attached to them, means for moving one of the shafts 80 endwise, collars attached to the shaft adapted to be moved endwise, and prongs of varying length carried by the collars, said prongs serving to successively engage and release the rollers as the shaft is moved endwise.

ERNEST JOSEPH MARTIN.
